M. E. TANDY

PISTON CORE CHILL AND MOLD

Filed Nov. 11, 1924

Patented Feb. 23, 1926.

1,574,454

UNITED STATES PATENT OFFICE.

MAYBEL E. TANDY, OF HANFORD, CALIFORNIA.

PISTON CORE CHILL AND MOLD.

Application filed November 11, 1924. Serial No. 749,246.

To all whom it may concern:

Be it known that I, MAYBEL E. TANDY, a citizen of the United States, residing at Hanford, in the county of Kings and State 5 of California, have invented certain new and useful Improvements in Piston Core Chills and Molds; and I do hereby declare the following to be a full, clear, and exact description of the invention, such as will 10 enable others skilled in the art to which it appertains to make and use the same.

The invention relates to metal founding and chiefly to the casting of metal pistons for internal combustion engines and provides a core chill and mold which may be 15 readily assembled and easily taken apart after the piston has been cast, the core and mold being of metal and sustained in proper position when assembled by means of a centering device, the latter also serving as 20 means to facilitate the withdrawal of the core when removing the latter from the piston.

Other objects and advantages will be apparent and suggest themselves as the nature 25 of the invention is understood.

While the drawings illustrate an embodiment of the invention it is to be understood that in adapting the same to meet different 30 conditions and requirements, various changes in the form, proportion and minor details of construction may be resorted to without departing from the nature of the invention.

35 Referring to the accompanying drawings forming a part of the specification,

Figure 1 is a sectional view of a piston core chill and mold embodying the invention.

40 Figure 2 is a horizontal sectional view on the line 2—2 of Figure 1,

Figure 3 is a horizontal sectional view on the line 3—3 of Figure 1, and

Figure 4 is a side view of the core.

45 Corresponding and like parts are referred to in the following description and designated in the several views of the drawings by like reference characters.

The numeral 10 denotes the body of the 50 mold, 11 the base and 12 the cap, the latter having a centrally disposed opening and a boss 13 in line with the opening, both the cap and the base having its marginal portion countersunk to receive opposite ends of

55 the body 10. The base 11 is provided with a central opening 14 to receive a centering

pin 15 whereby the core is properly positioned and held from displacement.

The core is of sectional formation and may consist of cast iron, steel, copper or 60 other suitable metal and comprises a center piece 16 and quarter sections 17, the center piece 16 forming a wedge to hold the quarter sections 17 in proper relationship to form the core. Half round notches 18 are 65 formed in the meeting edges of corresponding quarter sections 17 and result in the formation of the bosses which receive the ends of the wrist pin, whereby the connecting rod is attached to the piston. A transverse slot 70 19 is formed in the upper end of the center piece 16 and registers with spaces 20 formed between the upper ends of corresponding core sections 17 and this slot 19 and spaces 20 receive the metal which forms the bracing 75 web which connects the wrist pin bosses of the piston. The centering pin 15 is threaded into an opening 21 formed in the lower end of the center piece 16 and also serves as convenient means for withdrawing the 80 center piece from the piston after the latter has been cast so that the quarter sections 17 may be moved inwardly to clear the piston bosses preliminary to withdrawing the core sections 17 from the piston. 85

What is claimed is:

1. A sectional chill and core for a piston casting mold the same comprising a center section and quarter sections at opposite sides of the center section, the latter being of 90 wedge formation to facilitate its withdrawal, corresponding quarter sections having matching notches to form wrist pin receiving bosses and the quarter sections being applicable and removable by direct lateral movement. 95

2. A sectional chill and core for a piston casting mold the same comprising a center section and quarter sections of substantially the same length as the center section at 100 opposite sides of the center section, said quarter sections being applicable and removable by direct lateral movement, corresponding quarter sections having matching notches to form wrist pin receiving bosses, the center piece having a transverse slot in its upper end and the meeting edge portions of the quarter sections being cut away to provide spaces which register with said transverse slots whereby to form a reinforcing web for said wrist pin bosses. 110

3. A piston mold comprising a body, a

cap, a base closing the bottom of said body, both the cap and base having marginal portions countersunk to receive corresponding ends of the body, the base having an opening to receive the centering pin of a core, and the cap having a central opening and a

10 nipple or boss in line with said opening to receive the molten metal when pouring the piston, and the latter having an opening in its lower end to receive a centering pin, and the quarter sections having matching notches in opposing sides and having portions cut away to provide recesses to register with the transverse slot in the upper end of the center piece.

15 4. A piston mold comprising a body, a

nipple or boss in line with said opening to receive the molten metal when pouring the piston, and a sectional core comprising a center piece of wedge form and quarter sections at the sides of the center piece applicable and removable by direct movement, the latter having an opening in its lower end to receive a centering pin, and the quarter sections having matching notches in opposing sides and having portions cut away to provide recesses to register with the transverse slot in the upper end of the center piece.

20 In testimony whereof I affix my signature.

25 MAYBEL E. TANDY
